UNITED STATES PATENT OFFICE

GUSTAV EGLOFF, OF CHICAGO, ILLINOIS, ASSIGNOR TO UNIVERSAL OIL PRODUCTS COMPANY, OF CHICAGO, ILLINOIS, A CORPORATION OF SOUTH DAKOTA

PROCESS OF DESULPHURIZING CRACKED HYDROCARBONS

No Drawing.

Application filed June 26, 1926. Serial No. 118,823.

This invention relates to improvements in process of desulphurizing cracked hydrocarbons, and refers more particularly to the desulphurizing of the cracked products such as gasoline and like constituents formed by the cracking process, so as to remove therefrom objectionable sulphur compounds, although in its broader aspects, the invention may not be limited to such particular use.

10 In the cracking of petroleum oils, as for example, California petroleum containing sulphur compounds, it has been found that the gasoline produced by the cracking process, contains in some instances as high as 15 1% of sulphur. Furthermore, that it is necessary to use as much as 25 pounds of sulphuric acid per barrel of gasoline, to remove the sulphur, and further, there is a treating loss of upwards of 20% of the gaso- 20 line.

It is obvious to one skilled in the art, that this is a very uneconomical operation. The present invention is directed to avoid this expensive treatment, and also the high gaso- 25 line loss referred to.

In carrying out the invention, the cracked hydrocarbons preferably in vapor form, are subjected to the chemical action of regulated quantities of oxidizing gas preferably in the 30 presence of a silent electric discharge. If desired however, the vapors may be condensed and revaporized, although this would be in most cases, an unusual operation. Carrying out the invention, I take the 35 cracked hydrocarbon vapors which may be at a temperature of say 500° F. more or less, as they leave the dephlegmator, and pass them to a suitable still or other receptacle which may be externally heated or not, as 40 the case may be. Here the hot vapors are subjected to the chemical action of regulated quantities of air or ozone, or other oxidizing gas in the presence of an electric discharge. This electric discharge may take the form of 45 a uni-directional flow of electrical energy from one pole to the other as it passes through the hydrocarbon sulphur gases and oxidizing gas. The simultaneous action of oxidizing gas and electrical energy selectively reacts 50 with the sulphur compounds present in the

gaseous mixtures, hence producing a substantially sulphur free gasoline condensate after the vapors pass through a water condenser.

This process may be carried out under a temperature condition of approximately 55 500° F. more or less, while passing in an oxidizing gas such as air upward of 10% of the hydrocarbon sulphur gas mixture, while simultaneously passing an electrical energy 60 under a high voltage low amperage current. 65

The result of this treatment not alone brings about a desulphurizing action, but also polymerizes the unstable unsaturated hydrocarbons so as to eliminate gum forming constituents which may be present in the hy- 65 drocarbon sulphur gaseous mixture.

This system may be operated, dependent upon the refractiveness of the sulphur compounds present in the gases, under substantially vacuum conditions as low as 5 millimeters, or under superatmospheric pressures as high as several hundred pounds to the square inch. 70

I claim as my invention:

The method of treating dephlegmated 75 cracked hydrocarbon oil vapors as they leave the dephlegmator of an oil cracking apparatus, which consists in subjecting the hot vapors to the action of ozone in the presence of a silent electric discharge. 80
